UNITED STATES PATENT OFFICE.

HERMAN H. WOLTER, OF MERIDEN, CONNECTICUT, ASSIGNOR TO THE MILLER COMPANY, OF MERIDEN, CONNECTICUT, A CORPORATION OF CONNECTICUT.

DESIGN FOR A LAMP STANDARD.

Application filed May 17, 1928. Serial No. 26,728. Term of patent 3½ years.

To all whom it may concern:

Be it known that I, HERMAN H. WOLTER, a citizen of the United States of America, residing at Meriden, in the county of New Haven and State of Connecticut, have invented a new, original, and ornamental Design for a Lamp Standard, of which the following is a specification, reference being had

to the accompanying drawing, forming a part thereof.

The figure is a perspective view of a lamp standard, showing my new design.

I claim:

The ornamental design for a lamp standard, as shown.

HERMAN H. WOLTER.
